(57) **CLAIM**

The ornamental design for a device for aircraft controls as shown and described.

DESCRIPTION

The patent or application file contains at least one drawing executed in color. Copies of this patent or patent application publication with color drawing(s) will be provided by the Office upon request and payment of the necessary fee.

1. Device for aircraft controls

1.1 : Perspective view of a device for aircraft controls

1.2 : Perspective view thereof shown in an alternative configuration of use

1.3 : Perspective view thereof shown in an alternative configuration of use

1.4 : Perspective view thereof shown in an alternative configuration of use

The green color overlay depicts portions of the device for aircraft controls that form no part of the claimed design.
